UNITED STATES PATENT OFFICE

RUDOLPH A. OESMAN, OF BROOKLYN, NEW YORK

CLOTH HANDLING MACHINE

Application filed September 18, 1926. Serial No. 136,366.

This invention relates to improvements in cloth handling machines and additionally to a machine adapted to lay out predetermined lengths of cloth for suiting on a table or other support.

In clothing factories and the like, where large numbers of ready to wear suits are tailored, it is customary to take a bolt of cloth and lay it out on a cutting table in predetermined lengths and in superimposed relation, in one, two, or three suit lengths and sometimes more, from which a cutter afterwards cuts a predetermined number of suits of certain sizes and with little or no waste.

In cutting several lengths of cloth and laying the cloth in superimposed relation on the table, it is necessary that the nap of all layers be in the same direction, so that the suit cut from the cloth will have the nap running in the proper direction. It is commonly experienced in these factories that the cutters who are highly paid experts in this line fail to get the nap of the cloth in the right direction, due to failure of giving the proper concentration to their work, and as a result of which greater lengths of cloth are frequently cut than are necessary as well as some pieces of cloth being laid with the nap in the wrong direction. This results in a substantial amount of waste at the present time, and under these conditions of procedure, and it has been found substantially impossible to get the cutters to give the proper attention to these matters in order to prevent the waste and thereby obtain the highest efficiency in production with substantial economy.

This invention is designed to replace the cutter and one or two helpers which are usually necessary and to automatically lay any predetermined number of pieces of cloth in superposed relation on a cutting table ready for cutting in accordance with suiting patterns. In operation, the machine will automatically feed the cloth to a suitable holding device on the end of the table so that the ends are all placed in coincident relation, after which the machine lays out a predetermined length of the cloth and through the operation of suitable mechanism cuts the

same to the proper length, with the nap always in the same direction.

This invention contemplates the provision of a machine which will perform this work in a highly efficient and economical manner, 55 in order to considerably increase the production of suiting and at the same time reduce the cost incident to the operation of cutting.

In the provision of this machine, it is contemplated to produce a substantially greater 60 output for a single cutting table than has been heretofore attainable, and as a result, the amount of cloth space for the cutting operation may be considerably reduced, through the use of a reduced number of tables for a 65 predetermined output of cut suiting.

The invention comprehends additional improvements in the details of construction and arrangement of parts, in order to obtain a 70 simple and efficient machine, all of which are more particularly pointed out in the following detailed description and claims directed to the preferred form of the invention, it being understood, however, that various changes 75 in the size, shape and arrangement of these parts together with the cooperation therebetween may be made, without departing from the spirit and scope of the invention, as herein set forth.

In the drawings, forming a part of this application,

Figure 1 is a side elevation of a cutting table, having the present invention applied thereto, and showing several layers of cloth of predetermined length and all of the same 85 length laid on the table and having the ends severed, the carriage being at the rear end of its stroke ready to start the forward motion for supplying the next layer of cloth and the 90 end thereof to the holding mechanism, preparatory to laying it on top of the several lengths already positioned on the table.

Figure 2 is a front elevational view of the carriage structure forming the subject matter 95 of this invention.

Figure 3 is a plan view of the carriage.

Figure 4 is a side elevation of the carriage similar to that shown in Figure 1, on the enlarged scale, as shown in Figures 2 and 3.

Figure 5 is a sectional view, taken on the line 5—5 of Figure 2.

Figures 6 and 7 are sectional views, similar to Figure 5, showing progressive operations in presenting a cloth end to the holding mechanism, prior to the operation of the device to lay the cloth on the table in the return stroke of the carriage.

Figure 8 is a view similar to Figure 4, showing a portion of the holding mechanism as in Figures 5, 6, and 7, with the parts positioned as at the beginning of the movement of the carriage to lay the cloth on the table as it moves away from the holding mechanism on what may be termed the return stroke.

Figure 9 is a vertical transverse section, through the end portion of the cutting table and the holding mechanism, showing the details of construction thereof, taken on the line 9—9 of Figure 5.

Figure 10 is a sectional view, taken on the line 10—10 of Figure 9.

Figure 11 is a sectional view, taken on the line 11—11 of Figure 9, the scale being enlarged.

Figure 12 is a sectional view, taken on the line 12—12 of Figure 4.

Figure 13 is a sectional view taken on the line 13—13 of Figure 12.

Figure 14 is a sectional view, taken on the line 14—14 of Figure 12.

Figure 15 is a rear elevation of the control disc for governing the operation of the carriage and stopping the same after a predetermined number of layers of cloth have been placed in superimposed relation.

Figure 16 is a sectional view, taken on the line 16—16 of Figure 12.

Figure 17 is a sectional view, taken on the line 17—17 of Figure 12.

Figure 18 is a sectional view, taken on the line 18—18 of Figure 5.

Figure 19 is an inside elevational view of one of the movable block members, showing the cloth guiding tongue and the operating mechanism therefor.

Figure 20 is a sectional view, taken on the line 20—20 of Figure 12.

Figure 21 is a perspective view of the operating plunger on the carriage, movable to operate the cloth holding mechanism in feeding a cloth end into said mechanism.

Figure 22 is a front elevational view of one end of the carrier, showing one of the movable block members carried thereby and a dash pot attachment in longitudinal section for controlling the lowering movement of the block members and parts carried thereby upon release of the pawl mechanism shown in Figure 18.

Referring particularly to Figure 1, a cutting table is indicated at 1, which is of the usual construction already known in the art, and which for the purpose of this invention is provided with channels at opposite edges

thereof as shown in Figure 2, formed with rack teeth as indicated at 2, and more particularly shown in Figure 4.

The mechanism forming the subject matter of this invention, is mounted on this cutting table 1, and includes the holding mechanism, which is generally indicated by the numeral 3 in Figure 1, while a movable carriage mechanism, which forms a cloth folding feeding and operating mechanism for the entire device is indicated at 4, referring to the construction as a whole.

Particular reference will now be made to the description of the movable carriage mechanism indicated generally by the numeral 4, which is illustrated throughout numerous views of the drawings and particularly Figures 2 to 8 inclusive, while details are shown in the remaining figures. The carriage mechanism carrier or cloth carrying means as it is hereinafter termed, includes a pair of spaced side frame members 5 positioned at opposite sides of the machine and consisting of upper and lower longitudinal bar members 6 joined by the vertical bar members 7 at a plurality of points intermediate the ends as well as at the opposite end portions. A suitable motor platform 8 extends between said frames 5 and serves to

mount the same in spaced parallel relation in cooperation with the front connecting bar 9 joining the upper front corners of the side frames. At the rear ends of the side frames and between the upper portions is mounted the cloth holding basket 10, secured thereto in any suitable manner and in which the cloth to be cut in predetermined lengths is positioned after being folded according to the usual book fold method.

The free end of the cloth in the basket 10 is drawn upwardly and passed over the guide roller 11 which is provided with annular flanges at the opposite ends and journaled in bearings 12 in suitable bearing brackets 13, positioned on the upper edges of the side frame members 5 as clearly shown in Figure 4. The cloth is then drawn over this flanged roller 11, to the forward end of the frame and in this movement it is received in the guide tray 14, extending between the brackets 13 and from the forward portion of the bearings 12 to the forward end of the side frames as shown in Figure 5. At this point, the cloth is passed over the idler roller 15 and downwardly to the flanged guide roller 16 carried by the movable cloth feeding mechanism indicated generally by the numeral 17. This movable cloth feeding mechanism includes a pair of end members 18 which are slidably mounted on the inner sides of the movable block members 19, movably mounted in any desired manner, on the front uprights 7 of the side frame members 5. These movable block members 19 may be assembled on vertical bars 7 of the side frame in any suit-

able manner that may be found most expedient. Figure 19 illustrates the cloth feeding mechanism in which a lower tongue 21 joins the end members 18 and an upper tongue member 22 is formed at opposite ends with extensions 23 pivotally mounted at 24 on the end members 18. Spring latches 25 engage the notches formed in the portion 23 of the movable upper tongue member and are 5 adapted to hold it in adjacent but spaced parallel relation with respect to the lower tongue member 21. This upper tongue is formed throughout its surface with a plurality of small humps such as indicated at 26, 10 in Figure 19, which have shoulders at their forward ends and are adapted to prevent the retraction of the cloth after passing through the tongue member, and to assist in holding the cloth end, after cutting, in position 15 for presentation to the holding mechanism 3, when beginning the laying of the next layer on the cutting table. The dotted lines in Figure 19 illustrate the raised position of the movable upper tongue member 22, which 20 permits the insertion of a new cloth end between said members. Idler supporting wheels 27 are rotatably mounted on suitable stub axles 28 carried by the front portion of the lower longitudinal bars 6 of the side 25 frames 5 and are provided with toothed peripheries engaging in the rack teeth 2 formed in the cutting table, while the main supporting and driving wheels 29 formed with toothed peripheries riding in the racks 2 in 30 the cutting table are mounted upon the supporting shaft 30 journaled in a pair of opposite vertical bars 7 spaced from the rear end of the frame and at opposite sides of the basket 10 as clearly shown in Figure 4.

40 The side frame 5 at the left hand side of Figure 2, which will hereinafter be termed the left side frame is provided with bearings on the vertical bars 7 rotatably supporting the drive shaft 31 carrying the bevelled gear 32 intermeshing with bevelled gear teeth 33, 45 on the left hand drive wheel 29 as clearly shown in Figures 2 and 3, the bearings for the shaft 31 being indicated at 34. This shaft 31 carries a pair of spaced drive pulleys 35, 50 between which is an idler pulley 36 and aligned with these three pulleys on an intermediate shaft 37 journaled in bearings 38 on the upper ends of bars 7 is a drive pulley 39. A drive belt 40 is trained over the pulleys 39, 35 and 36 respectively for driving the shaft 31 in the same direction as the intermediate shaft 37, while a reversing belt 41 is 55 trained over the pulleys 39 and 35 and 36 respectively, for driving the shaft 31 in an opposite direction to the intermediate shaft 37. These belts are arranged in such a manner that one of the belts rides and engages on the idler pulley, while the other belt is engaged with one of the drive pulleys 35.

60 The intermediate shaft 37 is driven through

the bevelled gear connection indicated at 42, from the drive shaft 43 of the reducing gearing indicated generally at 44 of any suitable type for reducing the speed ratio between the drive shaft 43 and the shaft 45, connected by a suitable coupling with the armature shaft 46, of the electric motor 47. This electric motor is suitably mounted on the motor platform 8 secured between the side frames as clearly shown in Figure 3 and is of suitable power with suitable speed, preferably of the constant speed type of motor for producing a uniform movement of the carriage on the cutting table, throughout its stroke of movement. The shifting of the belts 40 and 41 controls the direction of movement of the carriage on the cutting table, and in order that the motion of the carriage in either direction may be suitably controlled, an operating lever 48 is pivotally mounted on the left side frame 45 as shown in Figure 4 at 49, and carries, through a suitable pivotal connection therewith, the belt shifting lever 50, provided with suitable fingers engaging at 55 opposite sides of the belts 40 and 41 and operable in its movement in a plane parallel with the left side frame to shift the belts 40 and 41, so that either of the belts may be placed in driving cooperation with one of the drive pulleys 35.

For automatically controlling the operation of the lever 48, a pair of shifting lugs 51 are removably and adjustably mounted on the edge portion of the cutting table, so that they may be set to operate the carriage mechanism 4 to change its direction of motion at a predetermined point in order that cloth will be laid on the cutting table to the desired length and automatically cut as will hereinafter appear.

A cam shaft 53 extends between the side frames 5 and is rotatably mounted in a pair of the vertically extending bars 7 of the side frame, as clearly shown in Figures 3 and 4. Operating cams 54 are rigidly mounted on the cam shaft 53 at the inner sides of the uprights 7 of the side frames, while a ratchet wheel 55 is mounted on the outer end of the cam shaft beyond the left side frame, as shown in Figure 4. As more particularly illustrated in Figure 13, this ratchet wheel is provided with a hub portion 55' which has a pair of diametrically opposite recesses 56, with which cooperates the pivoted pawl 57 mounted on the left side frame 5, and normally spring pressed into position by the leaf spring 58, secured to the vertical bar 7 of the side frame, as shown in Figure 4.

As shown in Figure 4, the left side frame 5 has one vertical bar 7 adjacent the forward end of the frame provided with an extension 59 extending rearwardly on which is pivotally mounted the operating quadrant 60. This operating quadrant is illustrated in detail in Figure 20 and at the forward end

70

75

80

85

90

105

110

115

120

125

130

thereof has a yieldable rack 61, provided with ratchet teeth for cooperation with the ratchet wheel 55, so that in an arcuate movement of the quadrant 60 downwardly from the position shown in Figure 4 to that shown in Figure 8, the cam shaft will be rotated one-half a revolution to produce an operation which will hereinafter be set forth. This operation of the quadrant member is effected through the medium of the lever 62, connected to the end of the belt shifting lever. This lever 62 is slidably mounted in the bearing 63, on the projection 59 from the vertical bar 7 of the side frame, as shown in Figure 4. The free end of this lever 62 is provided with a laterally extending head, operating in the slot 64, extending in close relation along the upper edge of the quadrant 60. A pin and slot connection 65 serves to limit the operation of the quadrant member 60, but is sufficient to permit its motion for rotating the cam shaft 53 a one-half revolution. The yieldable mounting of the rack 61, permits the return upward motion of the quadrant member 60, from the position shown in Figure 8 to that shown in Figure 4, without affecting or rotating the cam shaft 53. The face of the quadrant 60 adjacent to the side frame 5 is formed with a recess at 66, in which is mounted a resiliently projected pawl 67, movable in a path to engage the free end of the pawl 57, so that in the downward movement of the quadrant 60, the pawl 67 will engage the pawl 57 and move the same on its pivot so as to release the ratchet wheel 55 for rotation by the operation of the quadrant 60 through a one half revolution as above stated.

The operating cams 54 are adapted to engage the cross heads 68 for operating the plungers 69, of which they form a part, as shown in Figure 21. These plungers 69 carrying the cross heads 68 are slidably mounted in guideways 70 as shown in Figure 18, formed in the movable block members 19, while the operating slides 71 of shorter length than the plunger 69 are slidably mounted in the guide ways 70 alongside and inwardly of the plungers 69. The slide members 71 are provided with inwardly projecting studs on the inner faces thereof as shown in Figure 19, with which engage the forked ends of the levers 72, pivoted intermediate their ends on the inner faces of the movable blocks 19. The opposite ends are forked as indicated at 73, which extend over the shaft supporting the guide roller 16 of the cloth feeding mechanism so that by the movement of the levers 72 on their pivots by the operation of the slides 71, the cloth feeding mechanism will be moved forwardly or rearwardly to the position as indicated in Figures 5 to 8 inclusive, for feeding a cloth end to the holding mechanism 3 in the manner which will be hereinafter described.

The forward ends of the plungers 69 are formed with enlarged heads 74, so that the heads 74 and the cross heads 68 extend to the inner side of the plunger 69 to form stops for engaging the ends of the operating slides 71. It will be noted from the several views that the operating slides 71 are shorter in length than the distance between the head 74 and the cross head 68 on the plunger member, so that a predetermined amount of lost motion will exist for a purpose which will hereinafter appear, in order to properly time the operation of the cloth feeding tongues 20, and 21. The forward ends of the heads 74 are formed with bevelled faces for engagement in the correspondingly formed sockets 75 of the slidable operating blocks 76 for the cloth holding mechanism as shown in Figure 10, the various operative positions of these parts being shown in Figures 5 to 8 inclusive.

A cloth cutting mechanism is provided, which includes a T-shaped motion transmitting lever 77, having one end pivotally connected to the control lever 48 and the opposite end slidably extending through the projection on the bearing 34, on the left side frame 5, while the cross head portion of this T-shaped lever 77 is slotted, as indicated at 78, for slidably receiving the arm 79, to which is pivotally connected the operating hook 80, as shown in Figure 4. This arm 79 is slidably mounted in the bearing 81, on one of the movable block members 19, as shown in Figure 4, while a leaf spring 82 normally moves the operating hook 80 in one direction on its pivot, in order that it will engage with the shoulders of the star wheel 83 provided for operating the cutter bar. This star wheel 83 is adapted to operate the slidable plate member 84 carried by the movable block member on the left hand side frame 5, to one end of which is secured the cutter bar 86. The opposite end of the cutter bar 86 is secured to the pivoted link 87, mounted on the front face of the movable block member 19 on the right hand side frame 5 as shown in Figure 2. The cutter bar 86 is slotted adjacent its ends at 86' to receive the securing studs 86'' which rigidly mount the bar on the plate member 84 and quadrant 87 respectively. The slots 86' permit the proper setting of the cutter bar for smooth operation. The cutter 86 is given a slicing motion through the medium of the pivoted quadrant 87, and the curved slot formation indicated at 88, in the plate member 84. Coil springs 89 are attached to plate member 84 and quadrant 87, and to the block members 19 at the opposite ends to normally raise the cutter bar 86 into the position shown in Figure 2, ready for a subsequent cutting operation. It will be seen that in the operation of the star wheel 83 forcing the block 84 downwardly, the cutter bar 86 will be given a sweeping motion downwardly in order to

produce a draw cut on the fabric immediately at the forward end of the cloth feeding tongues.

A main control mechanism adapted to stop the operation of the machine when a predetermined number of layers have been piled on the cutting table and cut to the predetermined length desired is provided for controlling the operation of the motor 47 and is indicated generally by the numeral 90 in Figure 4, and shown in Figures 12, 15, 16 and 17, in detail. This mechanism includes a suitable switch mechanism including a stationary contact 91 and a resilient movable contact 92, mounted on a post of insulating material 93, secured to the extension 59 on the left side frame heretofore described. These contact arms are provided with opposed contact points adapted to normally engage with one another to close the electric circuit with the motor 47 and thereby permit the operation of the machine. The movable contact arm 92 is provided with a portion extending beyond the stationary contact 91, as shown in Figure 12 and formed with a curved head 94 at the end. A suitable control disc 95 is rotatably mounted on the extending portion 59 of the left side frame, as clearly shown in Figures 4 and 12 and is provided with an operating pin 96, adapted to engage the curved head 94 of the movable contact 92 and in passing thereunder to raise said movable contact for disengaging the contact point thereon from the contact point of the stationary switch member 91 and in this way open the circuit to the motor 47 and stop the operation of the machine. The disc 95 is rotatable through the operation of the resilient pawl 97, mounted on the quadrant member 60, through the lateral projection 98, thereon, which operates through the slot 99, in the extension 59 on the frame, as illustrated in Figure 15. This resilient pawl member is adapted to engage with the circumferentially arranged and equally spaced pins 100, so as to produce a step by step rotation of the disc 95 in each operation of the quadrant member 60. The switch operating pin 96 is disposed in circumferential relation with the pins 100 as clearly shown in Figure 15 and with which the resilient operating pawl 97 is adapted to engage in the operation of the disc 95. The shaft 101 mounts the control disc 95, as shown in Figures 16 and 17 and is provided at the end with an operating handle 102, by which the disc may be manually rotated, so that this disc may be set for a desired number of layers to be placed on the cutting table, in order that the machine may be set and started and thereafter operate automatically until a predetermined number of layers of cloth are piled in superimposed relation and cut to a predetermined length on the cutting table, at which time the control disc will operate to stop the machine. The disc 95 is permitted to

rotate in one direction only through the medium of a pawl 103, shown particularly in Figures 12 and 16, which cooperates with rack teeth formed on the face of the disc 95, as shown in Figure 16, adjacent to the extension 59. Circumferentially arranged numerals are provided on the face of the disc 95 adjacent to the extension 59 and are adapted to register with the opening 104 in the bracket 105, secured on the extension 59, of the left side frame, so as to indicate the setting of the disc 95 for a desired number of cloth layers to be cut and piled on the cutting table.

The members 19 and associated parts are adapted for step-by-step raising or upward motion, on the front upright 7 of the side frame and for this purpose, these forward uprights are provided with a series of ratchet teeth indicated at 106, in Figure 18, with which cooperates a spring pressed pawl 107, mounted in a recess formed in the slotted portion 20 of block member 19 and opening toward uprights 7. These pawls 107 support the block members 19 in any position of adjustment in a manner which will presently appear.

Now referring more particularly to the cloth holding mechanism indicated at 3 in Figure 1, and with particular reference to Figures 9 to 11 inclusive, the main housing 108 of inverted U-shaped construction is provided with channel portions 109 formed at the free ends of the bottom adapted to fit on the cutting table 1. Suitable means may be employed in securing the ends 109 rigidly to the cutting table 1. The sides of this housing 108 are provided with guides 110 for the movable housing 111 of the holding mechanism in which is rotatably mounted an operating shaft 112, for the mechanism adapted to hold the ends of the cloth in place on the cutting table 1. A pawl and ratchet mechanism shown in Figure 11 includes the ratchet wheel 113 mounted on the shaft 112, and the pawl 114 pivotally mounted on the top side of the housing 111, which permits rotation of the shaft 112 in one direction only. The opposite ends of the shaft 112 are journaled in bearings in the ends of the housing 111, and adjacent which are mounted the pinions 115 as shown in Figures 9 and 10, with which the teeth formed on block members 76 are adapted to mesh as shown in Figure 10, so that in the operation of the block members from the position shown in Figure 10, to the position shown in Figure 7, a one-half revolution of the shaft 112 will be produced, in order that the parts of the holding mechanism will operate in a manner as will now appear.

In order to provide for the meshing between the teeth of the block member 76 and the pinions 115, when operated by the plungers toward the back of the casing 111, and

permit the return movement to the position shown in Figure 10, under the influence of the spring 116 without engaging the teeth of the pinion 115, there is provided a special operating mechanism for the blocks, which includes slotted guide ledges 117, with which the projections 118 spaced unequal distances are adapted to cooperate and which are formed on the block members 76 on the opposite sides thereof as shown in Figure 9. These projections 118 are adapted to register with the slotted guide ledges 117 in the forward and rear positions or the positions at the opposite ends of the stroke of movement of the block members 76, so as to permit the movement of the projections 118 from the lower side to the upper side, or vice versa of the guide ledges 117. A continuous guide ledge 119 is provided in spaced parallel relation above the slotted guide ledges 117 so as to limit the upward movement of the block members 76 in their operation.

The block member 76, shown in Figures 5 and 10 is in position ready to produce a one-half rotation of the shaft 112 through the operation thereof by the plunger 69. As the block member approaches the rear end of a stroke of movement in effecting this operation of the shaft 112, the rear end thereof rides upwardly on the elevating member 120 slidably mounted in the projection 121 on the casing 111, and pressed upwardly by the coil spring 122. As the projections 118 ride opposite their respective slots in the guide ledges 117, the elevating member 120 will force the block members 76 upwardly until the projections 118 strike the upper ledge 119, at which time the teeth will move out of mesh with the teeth of the pinion 115, and the spring 116 will return the block member to the forward end of the casing 111, where the projections 118 will register with their respective parts in the ledge 117 and drop to the position shown in Figure 10 concluding one cycle of operation. The block members at the opposite ends of the casing 111 operate in synchronism in the manner as above described. Suitable retaining plates 123 formed as illustrated in Figure 9 provide the guide ways for the block members 76 to slidably retain them in position to operate as above described.

In the lower portion of the housing 111 is mounted a stationary supporting shaft 124, on which are mounted a plurality of pairs of rotatable cloth holding and engaging elements, in which corresponding elements of the pairs are indicated by the numerals 125 and 126 respectively. Each of the cloth engaging elements 125 and 126 are independently rotatable on the stationary shaft 124, and are formed with pinion teeth at their adjacent ends as illustrated at 127 in Figure 9. The central portion of each element is formed with a projection having an arcuate cloth engaging foot 128. The opposite end of each

cloth holding element of a pair is formed with a ratchet 129 with which engages a holding pawl 130 carried by the retaining collar 131, there being a pair of such collars adapted to retain the cloth engaging elements of each pair in proper position on the shaft 124 against relative endwise movement. The pawls 130 prevent rotation of the cloth engaging element in more than one direction. Operating gears 132 and 133 respectively are mounted in adjacent pairs for operating the corresponding cloth holding elements of a pair indicated by the numerals 125 and 126. These operating gears 132 and 133 are provided with gear segment sections 134 in which a pair of said segment sections are provided on the periphery of each operating gear at a distance of one-fourth of the circumference apart, so that the segments 134 on each operating gear are formed within one-half of the circumference of said gear, while the gears 132 and 133 are so mounted on the shaft 112 that their gear segments are in diametrically opposite positions, so that one of the cloth engaging elements will be operated through one whole revolution of movement alternately, with the other, in each pair. This is to obtain a predetermined operation of the cloth holding mechanism, which will now be described.

For the purpose of describing the operation of the machine, particular reference will be had to Figures 1 and 5 to 8 inclusive.

With the machine constructed as above described, a bolt of fabric folded in the well known book fold manner in which the layers are in zig-zag relation on top of one another, is placed in the basket 10 and the end fed up over the flanged guide roller 11, downwardly along the tray 14, over roller 15, and down through the feeding mechanism over roller 16, and through channels 21 and 22, with the free edge terminating adjacent the free edge of the tongues of the feeding mechanism. This is accomplished by moving the upper tongue member 22 upwardly to the dotted line position as shown in Figure 19, in order to insert the end of the cloth between the tongues. The forward edges of these tongues are recessed as indicated at 135, in line with the positions of opposed cloth engaging elements 125 and 126 so as to permit the projection of parts of the tongues between these pairs of engaging elements, so that the end of the cloth may be effectively fed into the cloth holding mechanism. With the parts in the position shown in Figures 1 and 4 and the parts of the cloth holding mechanism as shown in Figure 5, the carriage mechanism 4 will move forwardly on the table toward the cloth holding mechanism 3, with the cloth feeding mechanism having the tongues thereof retracted as in Figure 4. As the carriage mechanism approaches the cloth holding mechanism 3, the operating arm 48 will

engage the stop 51 adjacent to the cloth holding mechanism 3 and in the subsequent motion of the carriage 4 forwardly, a slight movement of this lever will operate the levers 50 and 62 to move the quadrant member 60 downwardly for releasing the pawl 58 from engagement with the recess 56 in the ratchet wheel 55, so that a slight rotation of the cam shaft 53 will move the cam 54 engaging and holding the plungers in position as shown in Figure 4, upwardly to permit the rearward movement of the mechanism with the forward movement of the cloth feeding mechanism to the position shown in Figure 5. In the further motion of the carriage 4 toward the cloth holding mechanism 3, to the position shown in Figure 6, a further rotation of the cam shaft 53 will be effected by the operation of the quadrant member 60 which will move the cams 54 to the position shown in Figure 6 and project the plunger mechanisms forwardly, so that the angularly formed heads 74 will engage in the sockets 75 of the block members 76, and move these block members to produce a rotation of the operating shaft 112 of the cloth holding mechanism for bringing one set of rack teeth 134 on the operating gears 132 into engagement with the pinions 127 on the elements 125 of each pair so that the cloth engaging feet 128 thereof will be moved one-half a revolution to engage and seat on the top of the end portion of the cloth carried by the feeding mechanism 17 and held between the tongues 21 and 22 by engaging the portion of the cloth extending across the recessed portion of the tongues as indicated at 135 and through the weight of the housing and its associated parts firmly press this end of the cloth toward the cutting table 1, which it has been found will firmly hold the end of the cloth in the proper position as presented to the cloth holding mechanism by the carriage mechanism 4, as shown in Figure 6.

At this juncture, the carriage 4 moves still further forward, and in this further forward motion, the cam shaft 53 will be rotated through the remainder of a one-half revolution to position the parts as shown in Figure 7. It will be noted that the motion from the position shown in Figure 5 to that shown in Figure 6 does not affect the cloth feeding mechanism due to the lost motion between the operating slide 71 and the plunger member 69, while in the operation of the parts from the position shown in Figure 6 to that shown in Figure 7, the cloth feeding mechanism is moved from its forwardly projected position to the rearwardly projected position, and the cloth end is effectively held by the holding mechanism. In this further movement of the parts to the position shown in Figure 7, it will be noted that the plunger mechanism is fully projected so that the block member 76 is moved to the rear position in

the housing 111, as shown in dotted lines in Figure 7 to complete a one-half revolution of the shaft 112, which brings one group of rack teeth on the operating gears 133 into cooperation with the pinion teeth on the cloth holding elements 126 of each pair, so as to move the arcuate feet 128 thereon out of engagement from under the end of cloth just presented to the cloth holding mechanism, and to the upward position as shown in Figure 7, ready for a subsequent operation to engage a new end of cloth. Now that the end of the cloth is held by the holding mechanism 3, as heretofore described and the parts positioned as shown in Figure 7, the full stroke of operation of the control lever 43 will have been completed. This positions the parts as illustrated in Figure 8, that is, the cutting mechanism will have the bar member 77 and the operating hook means 80 moved so that the hook member will engage over the adjacent shoulder on the spur wheel 83 as shown in Figure 8, while the operating quadrant 60 will be at the lower limit of its zone of movement and in its return motion from the position shown in Figure 8 to that shown in Figure 4 will idle while the rack 61 will yield to permit the teeth to ride over the ratchet teeth on the gear 55. The pawl 57 will hold this gear and the cam shaft in the position shown in Figure 8. The belt shifting lever 50 will have, in the operation of the arm 48 shifted the belts 40 and 41 so that the belt 40 will be on the idler pulley and the belt 41 on the reverse pulley, so as to permit the operation of the carriage mechanism 4 from the position shown in Figure 8, toward its rear limit of movement as shown in Figure 1. In this operation of the parts, the carriage moving rearwardly with the end of cloth held by the holding mechanism 3 will pull out a length of cloth and evenly lay the same on the cutting table 1, either directly on the table or on top of the layers already positioned on the table.

As the carriage reaches its other limit of movement shown in Figure 1, the arm 48 will engage the rear stop 51 as shown in Figure 1 and be moved from the position shown in Figure 8 to that shown in Figure 4. In this motion, the operating quadrant 60 will be returned to the position shown in Figure 4 from that of Figure 8 while the cutting mechanism will be operated so that the spur wheel will be rotated one-fourth a revolution which will force the block member 84 downwardly and produce the sweeping cutting operation of the cutter bar 86, so that the length of cloth laid on the table may be cut from the end held in the holding mechanism, at the predetermined length for which the stop 51 is set, which for instance may be what is referred to in the art as a three suit length, that is, a three suit length is desired by the cutter in order that he may cut three

suits from the predetermined length of the cloth with the least amount of waste. One, two, four or five suit lengths may be cut by the operation of the mechanism, if desired, 5 through the setting of the stop mechanism 51 at the proper point, in accordance with the scale shown and indicated at 136 on the edge portion of the cutting table. Any other length of cloth desired may also be cut by 10 properly positioning the stop on the cutting table. This operation of the lever 48 will then position the parts as shown in Figure 4 and the carriage will move forwardly toward the cloth holding mechanism to repeat its 15 operation in the manner above described for laying the next layer of cloth on top of this one already laid.

In order that the cloth feeding mechanism 17 will be moved upwardly so as to clear the 20 cloth laid on the table in its reciprocating movement back and forth thereon, the block members 19 are movably mounted on the uprights 7, and supported in an elevated position by the resilient pawls or latches 107, as 25 shown in Figure 18, and above described. In producing the upward motion of these block members 19, a cooperation between the plunger 69 and the block member 76 is utilized, through the formation of the socket 75 30 and the head 74 on the plunger with angular faces. At the end of the forward stroke of movement of the carriage 4 as shown in Figures 7 and 8, these angular faces cooperates so that as the housing 111 is raised to the 35 thicknesses of cloth held on the table, the angular faces cooperating to raise the block members 19 a corresponding amount and thereby always maintain the feeding mechanism 17 in spaced relation above the layers of 40 cloth placed in superposed relation on the cutting table, as clearly shown in Figure 1, in order that the cloth cut and laid on the table will not be interfered with in the subsequent placing of other layers in superposed relation 45 thereon. The elevating member 120 assists in this raising operation. That is, when the plungers are fully engaged with blocks 76, feet 128 have engaged on top of the cloth ends which raises the housing slightly with 50 each additional thickness of cloth, throwing the angular faces out of alignment and giving the plungers an upward lifting movement to realign said faces, while the upward movement of the block members 76 at the end of 55 the stroke, also aids in raising the blocks 19. The power feed cable for the electric motor is illustrated in Figure 1 at 137 which may be controlled by a manually operated switch 138. In order to provide for the reciprocating 60 motion of the carriage, the cable is formed with divided conductors 139 which if desired are movable on the supporting wire 140, so that the carriage may freely move back and forth and properable connections maintained 65 with a source of power and the carriage.

In order to prevent the sudden dropping of the block members 19 which is likely to damage the parts carried thereby and the machine, at the end of a carrying and cutting operation by the machine, through the 70 release of the latches 127, it may be found desirable to provide a cushioning mechanism for this lowering motion of the block members 19 as shown in Figure 22. This mechanism includes a dash pot structure having 75 a cylinder 141 mounted on a projection or supporting bracket 142, secured to the side frame 5 of the machine. A piston is mounted for reciprocation in the cylinder 141 and has its piston rod 143 extending through the 80 upper end thereof and in slidable relation and provided with a pair of stops 144 in spaced relation thereon for cooperation with the bracket 145 secured to the block members 19. In the upward motion of the block members 19, the bracket member 145 will engage the upper stop 144 and move the piston upwardly in the cylinder letting a charge of air into the cylinder through the air opening 85 in the cap on the upper end thereof, which will pass around or through the piston mechanism in any suitable manner as well known in the art, such as in an ordinary tire pump. In the construction of these devices, while in the downward motion of the 90 block 19, the bracket 145 will engage the lower stop member 144 and the piston will then, through the gradual release of air by the vent 146 cushion the downward movement of the block members and prevent the 95 sudden dropping of the same. In each operation of the quadrant members 60, the resilient pawl 97 is operated to move the disc 95 one step of movement. Should three 100 layers be desired to be laid on the table and cut to a predetermined length, the handle 102 is operated to position the numeral 3 for view through the opening 104, so that the carriage mechanism 4 will reciprocate three 105 times in each direction to lay and cut the 110 three lengths of cloth on the cutting table in superimposed relation and as the carriage moves toward the holding mechanism to present the end of the fourth length, it 115 will be seen that as the parts move to the position shown in Figure 8, the rotation of the quadrant member 60 to the position shown will rotate the disc 95 to move the projection or stop member 96 into engagement with the resilient switch member 92 120 and break the circuit to the electric motor 47 for thus stopping the machine. Should a greater number of layers of cloth be desired on the cutting table, the disc member 95 is rotated by operating handle 102 to position the desired number to view through the opening 104. In this way automatic operation 125 of the machine is obtained, which operation will result to lay a predetermined number of cloth layers on the table and cut the 130

same to the predetermined length to which the stops 51 are set regardless of the starting position of the carriage mechanism 4. The mechanism will always stop in the position 5 shown in Figure 8, adjacent to the cloth holding mechanism 3.

It will thus be clear from the foregoing description that a comparatively simple and efficient mechanism is provided with the 10 parts properly timed and cooperating to hold and feed cloth into a suitable holding mechanism which is automatically operated to firmly grip the cloth and hold the same on the table while the carriage mechanism moves 15 away from the holding mechanism and lays out the predetermined length cutting the same at the desired length through the operation of the cutter bar 86. In this way a waste of material is prevented through the cutting of 20 a greater amount of material for a certain number of suits than is necessary and often done by cutters, when manual labor is used, through inadvertence and carelessness, and in addition the nap of the cloth is always 25 maintained in the same direction for the reason that the bolt of cloth in the basket of the machine is never touched from the beginning to the finishing operation of the machine. In addition, the operation of the machine to produce any desired length of cloth 30 and any number of lengths in superimposed relation is entirely automatic by the proper setting of the parts and the control mechanism.

35 The particular construction and operation of the cloth holding mechanism forms an important feature of this invention aside from those above mentioned.

What is claimed is:

40 1. In a cloth handling machine, a table, a cloth end holding mechanism, and means having movement on said table for feeding cloth ends and operating said mechanism to grip said ends, adapted to automatically lay and 45 cut predetermined independent lengths of cloth on said table.

50 2. In a cloth handling machine, an automatically operable gripping mechanism, and means reciprocable relative to said mechanism adapted to feed, lay, and cut automatically independent predetermined lengths of cloth in its movement relative to said mechanism the nap on all cloth layers being unidirectional.

55 3. In combination, a support, a cloth holder thereon, and means for feeding cloth to said holder operable to automatically lay and cut predetermined lengths in superimposed relation on said support.

60 4. In combination, a cloth holder having movable cloth engaging elements, and cloth carrying means operable to feed independent cut cloth ends to said holder in coincident relation and operate said engaging elements.

65 5. In combination, a cloth holder having

movable cloth engaging elements, means operable to feed cloth ends to said holder, means for operating said engaging elements to grip the cloth ends, and means for operating the first mentioned means to automatically lay and cut predetermined lengths of cloth on a support having cut ends retained in said holder in coincident relation. 70

6. In combination, cloth holding means, reciprocable cloth carrying means, means carried by the last named means for feeding cloth ends into said holding means, means operable in the reciprocation of said carrying means for cutting cloth in predetermined lengths, and operating means for the carrying means and the cutting means. 75

7. In combination, cloth holding means, reciprocating cloth carrying means, means on the last named means for positioning cloth ends in the holding means, actuating means for operating the holding means to grip cloth ends, cloth cutting means, and operating means for operating said carrying means, the actuating means and the cutting means. 85

8. In combination, cloth holding means, reciprocating cloth carrying means, means for presenting cloth ends to said holding means carried by the second mentioned means, means associated with the second mentioned means for operating the holding means to grip presented cloth ends, a cutter on the carrying means, means for operating said carrying means, and means operable with the carrying means for controlling the operation thereof and adapted to operate said holding means and cutter in timed relation with said carrying means to cut cloth in predetermined lengths. 90

9. In combination, a cloth holder, a reciprocable cloth carrier operable to feed cloth ends to the holder and lay cloth lengths on a support, a cutter, and means operable for governing the movement of the carrier, operating the cloth holder and cutter in predetermined timed sequence to obtain predetermined lengths of cloth laid on the support. 105

10. In combination, a cloth holder, a reciprocable cloth carrier operable to feed cloth ends to the holder, and lay cloth lengths on a support, a cutter, governing means for timing the operation of the carrier, cutter and feed of cloth ends to the holder in a predetermined manner, and control means for automatically stopping the carrier at the end of a predetermined operation thereof. 115

11. In combination, a table, a cloth holder on the table, a movable cloth carrier on the table, means on the carrier to present cloth ends to the holder, cutting means, means for moving the carrier, and means operable in the movement of the carrier for operating the means for presenting cloth ends, and the cutting means in a predetermined manner to 125

lay and cut predetermined cloth lengths on the table.

12. In combination, a table, a cloth holder on the table, a movable cloth carrier on the table, movable means on the carrier for presenting cloth ends to the holder, means on the carrier for operating the holder to grip and hold said ends, a cutter operable on the carrier, means for operating the carrier, means operable in the operation of the carrier carried thereby for operating the movable means for presenting cloth ends, the holder, and the cutter, and controlling means movable in the operation of the carrier for producing 15 timed operation of the parts to lay and cut predetermined cloth lengths on the table.

13. In combination, a table, a cloth holder on the table, a movable cloth carrier on the table, cloth feeding means on the carrier 20 operable to present cloth ends to the holder, means on the carrier for operating the holder to grip and hold said ends, a cutter operably mounted on the carrier, means for operating the carrier, means operable in the operation of the carrier for operating the cloth feeding means, the holder operating means and the cutter in timed sequence, and adapted to control the movement of the carrier, and means operable by the last named means controlling 25 the operation of the means for operating the carrier.

14. In combination, a table, a cloth holder, a movable cloth carried on the table operable to feed cloth to the holder and lay 30 and cut lengths on the table, means for moving the carrier, means governing the operation of the carrier for controlling the length of cloth laid and cut on the table, and operating means for the last named means adjustably mounted on the table.

15. In combination, a table, cloth holding means on the table, cloth carrying and feeding means for feeding cloth ends to the holding means, and for laying and cutting predetermined lengths of cloth on the table, and means on the table for controlling the operation of the last named means in a predetermined manner.

16. In combination, a table, a cloth holder mounted on the table including a casing, a plurality of movable cloth engaging elements mounted for movement in the casing relative to the table, and operating means for moving said elements to engage cloth in a predetermined manner.

17. In combination, a table, and a cloth holder mounted on the table having a plurality of movable cloth engaging elements normally movable toward said table and adapted for cooperation therewith to hold cloth ends laid on the table and simultaneously grip and hold a new cloth end in substantially coincident relation to said laid ends.

18. In combination, a table and a cloth

holder mounted on the table including a casing, a housing movable in said casing, a plurality of pairs of cloth engaging elements, the elements of each pair being alternately operable for holding cooperation with the table, and means for operating said pairs of elements. 70

19. A cloth end holding mechanism comprising a casing adapted for mounting on a cutting table, a housing movable in said casing relative to the table, cloth engaging elements movably mounted in the housing adapted to engage and hold cloth ends on the table, and means for operating said elements in a predetermined manner for engaging 80 cloth ends. 75

20. A cloth feeding and carrying mechanism for cutting tables comprising a frame, means movably supporting said frame on the table, operating means for moving the mechanism on the table, means on the frame for supporting cloth, cloth feeding means operable in the frame, a cutter movably mounted on the frame, and means operated in the movement of said mechanism on the table for operating the cutter and feeding means in predetermined timed relation. 85 90

21. In combination, a support, cloth holding means on said support having a plurality of groups of cloth engaging elements successively operable to hold cloth ends on said support, and means for feeding cloth ends to said holding means and operating said engaging elements. 95

22. In combination, a cloth holder, means for automatically feeding cloth to said holder operable to lay predetermined lengths in superimposed relation on a support, and means controlling the last-named means for predetermining the number of layers placed on the support. 100 105

23. In combination, cloth holding means, automatically operable means for feeding cloth to said holding means and lay predetermined lengths in superimposed relation on a support, and means for automatically stopping the last-mentioned means after a predetermined cycle of operations. 110

24. In combination, cloth holding means, automatically operable means for feeding cloth to said holding means and laying predetermined lengths in superimposed relation on a support, stop means for the last-mentioned means, and cutting means for cutting said cloth operating in timed relation with the second-named means, said stop means being adjustable and operable at the end of a predetermined laying and cutting operation. 115 120 125

25. In combination, cloth gripping means, movable means for feeding cloth into the gripping means, and means for stopping the operation of the movable means at the end of a predetermined cycle of operation. 130

26. A cloth handling machine, including a movable carrier, reciprocable cloth feeding means on said carrier for feeding an end of cloth outwardly from and relative to the carrier in the reciprocation of said feeding means, and means controlling the operation of said cloth feeding means.

27. In combination in a cloth handling machine, a movable carrier, reciprocable cloth feeding means on said carrier, and means operable in the movement of the carrier for reciprocating said cloth feeding means to feed an end of cloth outwardly from the carrier.

28. In combination in a cloth handling machine, a movable carrier, automatic means controlling movement of the carrier, and cloth feeding means reciprocable relative to the carrier for feeding an end of cloth outwardly from the carrier controlled by said automatic means.

29. In combination in a cloth handling machine, a movable carrier, means controlling movement of the carrier, cloth gripping means for holding an end of the cloth during movement of the carrier, and cloth cutting means on the carrier, said gripping and cutting means being operated and controlled by the first named means.

30. In a cloth handling machine, a cloth holder formed for mounting on a table to hold the lengths of cloth at one end, movable cloth engaging and gripping elements carried thereby, and operating means for said elements.

35 31. A cloth holder for cloth handling machines operable on a table for laying cloth lengths thereon, comprising a movable housing mounted on and normally movable toward the table, rotary cloth engaging and gripping elements mounted in said housing, and means for rotating said elements to engage, grip and hold the cloth ends between said elements and said table.

32. A cloth holder for cloth handling machines operable on a table for laying cloth lengths thereon, comprising a plurality of independent rotary cloth engaging elements, means for supporting said elements for movement normally toward said table, and means for operating said elements in independent timed relation for engaging and holding cloth ends on said table.

33. A cloth holder for cloth handling machines, comprising alternately operable cloth engaging elements, and means for operating said elements to alternately engage and hold cloth lengths at one end.

34. A cloth holder for cloth handling machines operable on a table for laying cloth lengths thereon, comprising alternately operable rotary cloth engaging elements, means supporting said elements for movement toward said table, and operating means therefor to move alternate elements to engage and hold cloth against said table.

35. In combination, a cloth holder for cloth handling machines having cloth engaging elements, reciprocating means carried by said cloth holder operably connected to said elements, and an automatically operated carrier movable relative to said cloth holder for engaging and operating said reciprocating means and said elements.

36. A cloth laying machine comprising a cloth holding means, a reciprocable carriage for carrying cloth, a reciprocable cloth feeding mechanism on the carriage, and means for operating said cloth feeding mechanism on engagement with said cloth holding means, and for simultaneously operating the cloth feeding means to feed cloth ends into the holding means.

37. A cloth laying machine comprising a supporting table, a cloth holding device on one end of said table, a carriage reciprocable on said table, operating means for the carriage, a control lever for said operating means, and adjustable stops on said table for engaging and operating said control lever to control said operating means for causing reciprocating movement of the carriage on the table to and from the cloth holding device for cooperation therewith.

In testimony whereof I affix my signature.

RUDOLPH A. OESMAN.
